UNITED STATES PATENT OFFICE.

JOHN ALBERT BARBRAKE, OF CANTON, OHIO, ASSIGNOR TO THE SENG COMPANY,
OF CHICAGO, ILLINOIS, A CORPORATION OF ILLINOIS.

PEDESTAL-EXTENSION-TABLE LOCK.

No. 918,725.

Specification of Letters Patent. Patented April 20, 1909.

Application filed May 27, 1908. Serial No. 435.202.

To all whom it may concern:

Be it known that I, JOHN ALBERT BARBRAKE, a subject of the Emperor of Germany, residing at Canton, in the county of 5 Stark and State of Ohio, have invented a new and useful Improvement in Pedestal-Extension-Table Locks, of which the following is a specification.

The invention relates to means for engaging and drawing together the pedestal parts of a divided pedestal extension table, and for locking them in this relation; and the object of the improvement is to provide a simple and effective lock which can be applied to 15 any ordinary table without special preparation or change in the construction thereof, and which can be readily adapted and adjusted to operate with equal force and effectiveness at the edges of the pedestal parts 20 on each side of the center leg. This object is attained, in a general way, by mounting a transverse angular rock bar on the upper part of one pedestal part, with rock arms 25 slideable thereon, and by mounting mechanisms on the edges of the same pedestal part intermediate its top and bottom, adapted to engage and draw against posts on the opposite pedestal parts, with adjustable links 30 between the rock arms and the engaging devices, and means for operating and locking the device.

The invention, thus described in general terms, is illustrated in the accompanying drawings, forming part hereof, in which—

35 Figure 1 is a perspective view of a divided-pedestal extension-table, showing the pedestal parts extended and the lock exposed in open position; Fig. 2, an inner side elevation of one pedestal part, showing the lock 40 thereon in open position; Fig. 3, a vertical-longitudinal section of the pedestal parts showing the lock thereon in open relation in broken lines and in closed relation in full lines; Fig. 4, a fragmentary plan view of a 45 modified form of the rock bar and its connections; and Fig. 5, a modified form of engaging mechanism.

Similar numerals refer to similar parts throughout the drawings.

50 The divided pedestal parts 1 and 1^a, the attached bridging 2 and 2^a, the slides 3, 3^a and 3^b, the table top parts 4 and 4^a, with the center leg 5 and its attached bridging 6, may be of any ordinary form usually employed in 55 tables of this type; and the locking device is

composed of the handle 7, the handle-link 8, the rock-lever 9, the rock-bar 10, the bearings 11 and 11^a, the rock-arms 12, the clev- 60 ises 13, the adjustable links 14, the engaging mechanisms 15, all mounted on one pedestal part, as 1; and the engaging posts, as 16, which are formed or attached on the inside edges of the other pedestal part, 1^a.

The engaging mechanisms specially de- 65 scribed and claimed herein, are each com- posed of the vertically disposed bolt 17, located adjacent to the edge of the pedestal part, the links 18 and 18^a, one of which is ex- 70 tended to form the lever 19, and the bracket 20, which bracket is formed or attached on 75 the inner side of the edge of the pedestal part 1 intermediate the top and bottom thereof. The links are preferably parallel with each other and the respective ends are pivoted to the bolt and to the bracket. When the 80 mechanism is operated by means of the link- lever, the bolt is swung upward and downward, and to and from the pedestal part, and in this movement it is preferably main- 85 tained constantly in vertical position by means of the other link. The lower end of the bolt is preferably provided with the bevel- 90 ed faces 21 and 21^a, thus forming the point 22; and the normal relation of the parts when the lock is open, is preferably with the 95 parallel links in horizontal position, as shown in Fig. 1, and, by broken lines, in Fig. 3. In this relation of the engaging mechanism, the point of the bolt is adapted to pass freely over the upper side of the corresponding en- 100 gaging posts located on the opposing pedestal section, when the pedestal sections are closed nearly together; after which, by an operation of the mechanism, the bolt is thrown downward, and also inward toward the pedestal part to which it is attached, and in this movement, the inside bevel on the end of the bolt comes in contact with the upper rear side of the engaging post, and by a sliding action draws the same and the pedestal part to which it is attached toward the pedestal part to which the mechanism is at- 105 tached. A further movement of the bolt brings its inner vertical side 23 squarely against the rear side of the engaging pin, and thus the operation is completed by a direct and substantially horizontal pull of the en- 110 gaging parts.

One engaging mechanism is mounted on each side edge of the pedestal part, and an

engaging post on each corresponding edge of the opposing pedestal part, so that by an operation of the engaging mechanism, both sides of the pedestal parts are engaged and drawn together at the same time. In case the point of the bolt does not quite clear over the opposing engaging post when the pedestal parts are closed together, the outside bevel on the end of the bolt comes in contact with the upper forward side of the post, and the bolt is thus thrown upward to clear the post by the sliding of the bevel thereon.

The transverse rock-bar 10 is angular in cross section, preferably square as shown, and is rotatably mounted in the bearings 11 and 11^a, which in turn are secured on the upper side of the bridging 2 attached to the pedestal part on which the engaging mechanisms are mounted. The bearings 11^a are located at the ends of the rock-bar, and the bearing 11 is located intermediate the same, the latter bearing being preferably formed or securely attached on the inner end of the flat bar 24, which is secured to the bridging. To the outer end of the same flat bar, the shorter arm of the L-shaped handle 7 is pivoted. The rock-lever 9 is formed or attached at or near the middle part of the rock-bar, and, as shown, is preferably adapted to be transversely adjusted along the same, which adjustment is accomplished by inserting the bar in an angular aperture in the lever corresponding to the section of the bar. The free end of the lever is connected to the angle of the handle by means of the link 8, and the rock-bar is adapted to be rotated by an operation of the handle which is accomplished by grasping and manipulating the longer arm thereof.

Two rock-arms 12 are mounted on each end portion of the rock-bar, preferably inside the bearings 11^a thereof, by means of angular apertures corresponding to the cross section of the bar, so that like the lever they are adapted to be transversely adjusted by sliding along the bar, and a clevis 13 is pivoted to the free ends of each pair of rock-arms. The clevises are connected to the link-levers 19 of the engaging mechanisms by means of the links 14 which are made adjustable by passing the upper threaded ends 25 through apertures in the clevises and providing the nuts 26 above and below the clevises.

By means of these various devices and connections, the engaging mechanisms are adapted to be operated by the handle; and the pivotal connections of the ends of the handle-link with the handle and the rock-lever, are so located and arranged with reference to the pivot of the handle-arm, that when the lock has been operated to engage and draw the pedestal parts tightly together, the handle-link pivot will have passed through and beyond the line of the handle-

arm and rock-lever pivots, in the usual manner to a suitable stop, whereby the engaging mechanisms are locked. It is evident that by a sliding of the rock-arms and the clevises along the rock-bar, the same are always located directly over the engaging mechanisms, so that the same are operated by a direct pull; and that by the adjustment of the connecting-links 14, the engaging and drawing effect of each mechanism is adapted to operate with equal force, thus rectifying any imperfections in the making, assembling or location of the respective parts of the lock on the table.

A modified form of the rock-bar and its connections is shown in Fig. 4, wherein a clevis 13^a is employed in connection with a pair of rock-levers 9^a for connecting the same to the link 8^a, which is made adjustable by means of threading its outer end and providing the nuts 26^a thereon, in which case the links 14^a may be connected to single transversely slidable rock-arms as 12^a. It is evident that this modified form of the rock-bar and its connections can be employed in combination with the engaging and drawing mechanism above described without affecting the essential characteristics of the same. And, it is also evident, that the ordinary form of curved locking bolts 27, illustrated in Fig. 5, can be employed in connection with the operating devices hereinabove described, without affecting the essential characteristics of the same.

What I claim as my invention, and desire to secure by Letters Patent, is—

1. In a divided-pedestal extension-table lock an engaging mechanism, including a bolt adjacent to the edge of one pedestal part, two links having their respective ends pivoted to the bolt and to the same pedestal part, with means for operating and locking the mechanism, and a post on the other pedestal part adapted to be engaged by the bolt to draw the pedestal parts together.

2. In a divided-pedestal extension-table lock an engaging mechanism including a movable bolt adjacent to the edge of one pedestal part and having its ends beveled, two links having their respective ends pivoted to the bolt and to the same pedestal part, and a post on the other pedestal part adapted to be engaged by the bolt to draw the pedestal parts together.

3. In a divided-pedestal extension-table lock an engaging mechanism including a movable bolt adjacent to the edge of one pedestal part, two links having their respective ends pivoted to the bolt and to the same pedestal part, and a post on the other pedestal part adapted to be engaged by the bolt to draw the pedestal parts together.

4. In a divided-pedestal extension-table lock, a pair of posts on the sides of one pedestal part, a pair of mechanisms on the other

pedestal part adapted to engage the posts to draw the pedestal parts together, a transverse angular rock-bar on the same pedestal part with two pairs of transversely slidable rock-arms thereon, clevises pivoted to the 5 respective pairs of rock-arms, and links connecting the mechanisms and the clevises.

5. In a divided-pedestal extension-table lock, a pair of posts on the sides of one pedestal part, a pair of bolts on the other pedestal part adapted to engage the posts to draw the pedestal parts together, a transverse angular rock-bar on the same pedestal 10 part with two pairs of transversely slidable rock-arms thereon, clevises pivoted to the 15

respective pairs of rock arms, and connections between the clevises and the bolts.

6. In a divided-pedestal extension-table lock, a pair of posts on the sides of one pedestal part, a pair of bolts on the other pedestal part adapted to engage the posts to draw the pedestal parts together, a transverse angular rock-bar on the same pedestal part with transversely slidable rock-arms thereon, and connections between the rock- 20 arms and the bolts. 25

JOHN ALBERT BARBRAKE.
